UNITED STATES PATENT OFFICE.

WILLIAM GOETZ, OF WINNIPEG, CANADA.

HARNESS-TUG SECURING AND RELEASING DEVICE.

SPECIFICATION forming part of Letters Patent No. 788,826, dated May 2, 1905.

Application filed March 11, 1904. Serial No. 197,625.

To all whom it may concern:

Be it known that I, WILLIAM GOETZ, a subject of the King of Great Britain, residing at 5 Winnipeg, district of Selkirk, Province of Manitoba, Canada, have invented certain new and useful Improvements in Harness-Tug Securing and Releasing Devices; and I do hereby declare that the following is a full, 10 clear, and exact description of the invention, such as will enable others skilled in the art to which it appertains to make and use the same.

This invention relates to new and useful improvements in means designed for attaching and releasing horses to and from whiffletrees, whether single, double, or any multiple thereof; and it consists in certain features of novelty in the detail, construction, and arrangement thereof, all as will be hereinafter 20 more fully described, and particularly pointed out in the claims.

One of the objects of the invention is to provide a simple, economical, and durable means which may be connected with a whiffletree in such a manner that the more complicated parts may be easily protected from 25 accidental destruction and which will contain means whereby the device may be used for more quickly connecting the tugs of a harness thereto in a secure manner and which may be almost instantly placed in position for release of the horses when desired.

Another object is to provide cushioning means whereby all rattling of parts is obviated and the device is rendered entirely noiseless in operation.

Referring to the parts, in which similar numerals of reference indicate corresponding parts in all the views, Figure 1 is a top plan 40 view of my improved device, showing a portion of the pair of tugs connected thereto, as indicated in dotted lines in said figure. Fig. 2 is a rear end elevational view looking at the same as from the position of the driver; and Fig. 3 is an enlarged detached detail view, 45 partly in section, of one end of my improved whiffletree, the section being substantially a plan view thereof.

In the inclosed drawings, 1 indicates the

whiffletree, which may be of any preferred 50 material suitable for the purpose, which is provided at each end with the shield 2, the said shield being secured to the whiffletree in such a manner as to cover the cut-out portion 3 of the whiffletree which is shown in 55 Fig. 3. Pivottally connected with the end portion of the whiffletree 1, and preferably within a malleable casting 4 in the form of a ferrule adapted to be projected over the extreme end of the whiffletree 1, is a tug-hook 5, 60 having the forwardly-projecting nose portion 6 and the rearwardly-projecting curved extension 7 and the inwardly-projecting lever 8, all of which are formed of one integral casting, which may be of malleable iron or of 65 any other suitable material.

Between the shoulder 9 of the tug-hook 5 and the rearwardly-extending portion 7 is formed a seat 10 for engagement with the tug 11, (shown in dotted lines in Fig. 1,) the 70 seat being preferably located at such a convenient distance beyond the pivot 12, upon which the tug-hook is supported, that strain being exerted in the direction of draft will have a tendency to throw the tug-hook into 75 the position shown in dotted lines of Fig. 3. The inwardly-projecting lever 8 is provided with the extension 13, within which is formed 80 seats 14 for engagement with the curved inwardly-projecting extension 15 of the slidably engaging plate 16, which plate 16 is provided with the button-piece 17, which may consist of an ordinary set-screw held in position 85 therein or of any equivalent means for the purpose of projecting the member 16 longitudinally within the shield 2 for the purpose of engaging with the extension 13 of the tug-hook 5. The shield 2 is provided with an elongated slot 18, within which rides the member 17, the metal surrounding the slot 18 limiting the thrust of said member 17, and consequently the thrust of the engaging member 16. Upon the inner end of the member 16 is a hook 19, to which is connected a strap 20 by passing the said hook through a suitable 90 eye or opening in said strap for the purpose of forming a connection therebetween. Connected with the upper surface of the whiffle-

tree is a spring-plate 21, having the angular offset portion 22, which is adapted to contact with the tugs and be used when tugs with more than one hook-engaging opening is provided therein for the purpose of retaining the tugs in position upon the tug-hook 5.

It will be evident that where no spring-plate, as 21, is used the tugs are quite liable to become disengaged from their hooks 5, either in the event of the holes in the tugs becoming worn or in the event of such hooks being projected through any but the end holes, where a plurality of such holes are provided in the tugs.

15 To facilitate the retaining of the tugs in position, the angularity 22 is provided in the spring 21, such angularity embracing the upper edge portion of the tug, while the outwardly and downwardly bent extension thereof lies outside of and beyond the tug, thereby materially assisting in preventing accidental release of the tugs from the hooks 5 aforesaid.

Between the lever 8 and the adjacent face 25 of the whiffletree 1 is interposed a block 23, of rubber or some equivalent resilient material, which is adapted to completely fill the space between the lever 8 and the whiffletree 1 when the parts are in a locked position, 30 thereby holding the parts in their relatively fixed position and preventing any jarring or noise which might be incident to the rattling of the parts in use. In operating the device the parts are placed in the position indicated 35 in Fig. 1 and in full lines in Fig. 2, when the tug-hook 5 may be projected through the usual opening in the harness-tug 11, and thereby become interlocked therewith.

When it is desired to release the tug-hook 40 from engagement with the tug, all that is necessary is to pull down the strap 24, which is connected with the strap 20, thereby retracting the sliding plate 16 from engagement with the inner end 13 of the lever 8, whereby 45 draft upon the tug-hooks 5 will cause the same to rock upon their pivots 12 to approximately ninety degrees, whereupon the nose 6 will have become disengaged from the opening in the tug and the rearward extension 7 50 will be in such a position that the tug will slide freely therefrom.

During the operation of releasing the tug from the tug-hooks 5 the spring-plates 21 will perform the function of holding the tugs in 55 proper position to prevent their becoming entangled with the said tug-hook 5 by reason of the torsional strain on said tugs, and thereby permit a perfect release of the tug from the hooks 5.

60 I am aware of United States Patent No. 397,733 to Latshaw, and in using the device therein described have found that the tugs slip from the hooks when strain is taken off the tugs, as when descending a hill.

It is evident that the ferrule 4 upon the 65 tug should be of a special construction for the purpose of my invention, and to that end the frusto-conical body portion is substantially as heretofore formed, but is provided with a bifurcated extension 4^a between 70 which is provided a slot within which is pivoted the tug - hook 5. By using a piece of rubber, as 23, suitably secured in position by means of tacks, clips, or other engaging means, the said rubber being of sufficient size 75 to completely fill the space between the lever 8 and the contiguous face of the whiffletree 1, a close contact of parts is thereby established which will minimize or wholly prevent any rattling of the parts thereat. The ferrule 4 80 is preferably provided with grip members 25, adapted to be turned down over the spring 21 for the purpose of locking the same in position, the said spring 21 being also connected with the whiffletree by means of a screw 85 or suitable connecting-pin 26 at the inner end thereof.

In the description of my invention and in the claims wherever the same may be used I do not wish to be limited specifically to 90 straps, but wish it to be understood that any equivalent means well known in the arts may be substituted therefor and be within the spirit of my invention; nor do I wish to be limited in any particular to the specific construction or mode of operation hereinbefore described, as various detail modifications will readily suggest themselves to one skilled in the art to which my invention appertains, which modifications I wish it to be distinctly 100 understood are claimed by me except as hereinafter specifically limited in the claims.

Having thus described my invention, what I claim, and desire to secure by Letters Patent, is—

105 1. A whiffletree having cut-out portion 3 upon one side extending longitudinally thereof, a shield over said cut-out portion, a ferrule on the end of the whiffletree, a tug-hook pivotally mounted in said ferrule, and having 110 inwardly-projecting lever with seats, a slidably-mounted plate within said shield and having means coöperating with the shield to guide and limit the movement of the slide, and extension to engage the seats of the said 115 lever, a spring-plate on the whiffletree having angular offset portion, and grip members on said ferrule adapted to be turned down over the said spring-plate to lock the same in position, all substantially as shown and described. 120

2. The herein-described device for the purposes set forth, the same comprising a whiffletree having cut-out portion, a shield covering the same, a ferrule on the end of the whiffletree, a tug-hook pivotally mounted in said ferrule, and having inwardly-projecting seats, a slidably-mounted plate within said shield having means coöperating with the shield

to guide and limit the movements of the said sliding plate and an extension to engage the seats of said lever, a spring-plate on the whiffetree having angular offset portion embracing the upper edge portion of the tug, with the outwardly and downwardly bent extension thereof lying outside of and beyond the tug to assist in preventing accidental release of the tug from the tug-hook, and a grip member on the said ferrule and mounted

to be turned down over the spring-plate to lock the same in position, all as shown and described and for the purposes specified.

In witness whereof I have hereunto set my hand in the presence of two witnesses.

WILLIAM GOETZ.
